US00D935199S

(12) **United States Design Patent** (10) **Patent No.:** **US D935,199 S**
Wang (45) **Date of Patent:** **** Nov. 9, 2021**

(54) **MIRROR**

(71) Applicant: **ZHONGSHAN LEADER ELECTRICAL TECHNOLOGY CO., LTD**, Zhongshan (CN)

(72) Inventor: **Qin Wang**, Zhongshan (CN)

(73) Assignee: **ZHONGSHAN LEADER ELECTRICAL TECHNOLOGY CO., LTD**, Zhongshan (CN)

(**) Term: **15 Years**

(21) Appl. No.: **29/762,497**

(22) Filed: **Dec. 16, 2020**

(51) LOC (13) Cl. **06-07**

(52) U.S. Cl.

USPC **D6/300**; D6/309

(58) **Field of Classification Search**

USPC D6/300-314

CPC A47G 1/02; A47G 1/04

See application file for complete search history.

Primary Examiner — Deanna L Pratt

(57) **CLAIM**

The ornamental design for a mirror, as shown and described.

DESCRIPTION

FIG. 1 is a perspective view of a first embodiment of a mirror showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of the mirror showing my new design;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.
